CLAIM

The ornamental design for a jewelry box, as shown and described herein.

DESCRIPTION

FIG. 1. Is a perspective view of my jewelry box shown in the open position with the dotted lines showing being for illustrative purposes only for which no claim is made;

FIG. 2. Is a front perspective view of my jewelry box as shown in the closed position;

FIG. 3. Is a top plan view thereof;

FIG. 4. Is a bottom plan view thereof;

FIG. 5. Is a front elevational view thereof;

FIG. 6. Is a rear elevational view thereof; and,

FIG. 7. Is a right side elevational view thereof, with the left side being a mirror image thereof.
